FIG. 2.

Patented June 16, 1925.

UNITED STATES PATENT OFFICE.

CHARLES SCHWEINLE, OF MILWAUKEE, WISCONSIN, ASSIGNOR TO REFRIGO CORPORATION, OF MILWAUKEE, WISCONSIN, A CORPORATION OF WISCONSIN.

AUTOMATIC CONTROL FOR REFRIGERATING MACHINES.

Application filed May 29, 1924. Serial No. 716,811.

To all whom it may concern:

Be it known that I, CHARLES SCHWEINLE, a citizen of the United States of America, residing at Milwaukee, in the county of Milwaukee and State of Wisconsin, have invented certain new and useful Improvements in Automatic Controls for Refrigerating Machines, of which the following is a specification.

10 This invention relates to new and useful improvements in automatic controls for refrigerating machines and sets forth a device which is especially adapted for controlling the operation of electric motors employed 15 for driving compressors.

An important object of the invention is to provide a control for a compressor motor which is primarily governed by the temperature in the spaces being cooled by the 20 refrigerating plant.

A further object of the invention is to provide an auxiliary control for the compressor motor which is governed by the pressure of water being fed to the compressor 25 whereby the compressor motor will be automatically shut off when the water pressure drops below a predetermined point.

A still further object of the invention is to provide means, controlled by temperature, for governing the supply of water to a compressor, and means, controlled by the pressure of the water being supplied to a compressor, for governing the operation of the motor driving said compressor.

25 Another object of the invention is to provide temperature governed electrical means for controlling the supply of water to a compressor.

Other objects and advantages of the invention will be apparent during the course 40 of the following description.

In the accompanying drawings forming a part of this specification and in which like numerals are employed to designate like 45 parts throughout the same,

Figure 1 illustrates a front elevational view of the apparatus embodying this invention,

Figure 2 illustrates a vertical sectional view taken upon lines II-II of Fig. 1,

Figure 3 is a diagrammatical view of the electrical connection or wiring system for the apparatus illustrated in Fig. 1, and

Figure 4 is a detail side elevational view of a portion of the structure illustrated in Fig. 1.

In the drawings, wherein for the purpose of illustration is shown a preferred embodiment of this invention, the numeral 5 designates a water supply pipe which is intended to be connected to a suitable water main, or the like, and has connected thereto a substantially T-shaped coupler 6. This coupler 6 has connected to its branch 7 a nipple 8 which is connected at its outer end to a union 9 having a second nipple 10 leading therefrom to the coupler 11. This coupler has connected to the branch 12 a nipple 13 which is joined with a valve casing 14 having a pipe 15 leading therefrom to a compressor, not shown.

The T-coupler 6 is provided with a partition 16, extending transversely therethrough, having a valve seat 17 formed therein. This coupler is further provided with a flange end 18 to which is connected a leak preventing diaphragm 19 and the flange 20 of an extension 21 which is provided with a centrally apertured cap nut 22. Reciprocally mounted within the extension 21 and the coupler 6 is a valve stem 23 which projects outwardly through the aperture formed in the cap nut 22. This stem 23 is suitably connected to the leak preventing diaphragm 19, as at 19a, for preventing any leakage around this stem. The lower end of the stem is provided with a valve 24 which is adapted to engage the seat 17 for shutting off the flow of water from the pipe 5 to the nipple 8, the water pressure in the pipe 5 normally acting to retain the valve 24 upon the seat 17.

The coupler 11 is provided with a flanged branch 25 that is adapted to have connected thereto a diaphragm 26 and a flange 27 carried by the tubular extension 28. This extension is provided with a centrally apertured cap nut 29 within which is reciprocally mounted the stem 30. This stem 30 is suitably connected to the diaphragm 26, as at 26a, and is provided with a compression spring 31 which engages, at its lower end, the structure employed for connecting the stem 30 to the diaphragm 26, and further engages, at its upper end, a shoulder 32 formed in the extension 28. It will be

seen that this compression spring 31 normally operates for forcing downwardly upon the stem 31 and the diaphragm 26.

The valve casing 14 is provided with a 6 rotatable valve element 33 which is operated by the head 34 and is employed for positively shutting off the flow of water to the pipe 15 and the compressor, not shown.

Suitably connected to the extensions 21 10 and 28, as by the angle brackets 35, is a metallic box 36 which is provided with a hinged door 37 for closing the front of the same. Mounted within this box is a base 38, formed of slate or other insulating material, which is held therein by the bolts 39 having the spacers 40 and the nuts 41.

Suitably secured to this base 38 is a magnet frame including the back portion 42 and the bracket arms 43 and 44. Connected 20 to these arms 43 and 44 is a brass tube 45 which has wound therearound a magnetic coil 46, the tube 45 and coil 46 forming a solenoid. Loosely mounted within the brass tube 45 is a core 47 which is provided with 25 a stem 48 that projects outwardly of the upper end of the tube 45 and also extends through a suitable aperture formed in the arm 44 for the purpose of carrying a block 49 above this arm 44, the block 49 30 having a notch 50 formed therein. The upper portion of the back 42 of the magnet frame has secured thereto a solid core 51 which has wound therearound a magnetic coil 52.

Suitably secured to the arm 44 of the magnet frame is a double bearing element 53 which is employed for rotatably supporting the rod 54. This rod has mounted thereon a pawl 55 which is normally retained in 40 a forwardly inclined position, against the block 49, by a weight 56 which is carried by an arm 57 rigidly mounted upon the rod 54, it being again noted that this weight 56 will retain the pawl 55 in engagement with 45 the block 49 carried by the solenoid core stem 48 whereby movement of the block upwardly will cause the pawl 55 to engage the notch 50 formed in this block 49 for retaining the core 47 in an elevated position. 50 It, also, will be noted that the pawl 55 is so arranged in respect to the solid core 51 that when the magnetic coil 52 is energized, the pawl 55 will be attracted and moved into engagement with the outer end of the solid core 51.

Pivotedly connected, as by the bearings 58, to one side of the metallic box 36 is a lever 59 which projects into the box, through the opening 60 and has its end 61 normally bearing against the upper end of the block 49 carried by the stem 48. The outer end 62 of the lever 59 is adjustably connected to the upper end of the valve stem 23, as by the nut 63 threaded upon said stem, and is so formed that the upper end of the stem 23

will be permitted to move laterally of the end 62 of the lever 59. In other words, the end 62 is provided with a vertically extending opening 62^a which is of greater diameter than the stem 23 and permits a desired 70 amount of play of the latter therein.

Suitably connected to the insulating base 38, as by the bolts 64 is a reversely bent bracket 65 that is adapted for carrying the adjustable contact post 66, as best illustrated in Fig. 2. The end of the rod 54 opposite to the weight 56, is provided with a sleeve 67, formed of insulating material, upon which is positioned the clamp 68 which is in the form of a strap bent upon itself and 80 adjusted by means of the bolt 69. This clamp 68 is adapted for carrying a switch blade 70 which is secured thereto by the binding screw 71 and depends from the rod 54 for positioning its lower end in operative 85 relation with the contact post 66. It will be noticed, by inspecting Fig. 2, that when the pawl 55 is in engagement with the notch 50 in the block 49, the lower end of the switch blade 70 will be spaced from the contact end of the post 66. It will be understood that when the block 59 is positioned below the position illustrated in Fig. 2, that is without the pawl 55 received within the notch 50, the normal diameter of the block 90 95 59 will retain the pawl 55 substantially in engagement with the outer end of the solid core 51 and the lower end of the switch blade 70 will engage the contact post 66.

A three-pole switch is mounted upon the insulating base 38 and consists of the elongated insulating block 72 which is secured to the base by the bolts 73 and positioned outwardly therefrom by the tubular spacers 74. This elongated block 72 has secured thereto, as by the binding screws 74, three spaced, substantially L-shaped metallic contacts 75 which have their feet portion 75^a flushly engaging the lower longitudinal face 100 105 110 of the said block.

Journalized in the bearing brackets 76, carried by opposite longitudinal edges of the insulating base 38, is a rotatable rod 79 which is covered, between the bearing brackets 76, by an insulating sleeve 80. Adjustably secured to these elements 79 and 80 are the clamps 81, which are in the form of straps bent upon themselves and retained in position by the screws 82. Each clamp is provided with a projecting arm 81^a which carries a screw 83 having a tension spring 84 surrounding the same and held in place by a washer 85. Connected to the arm 81^a of each clamp 81 is a blade 86 having a brush 87 mounted upon its outer end. This brush 87 is provided with a suitable aperture which receives the screw 83 and is permitted to move relatively thereto, the spring 84 normally tending to hold the intermediate portion of the blade 86 in flush engage- 115 120 125 130

ment with the arm 81^a of the clamp 81. Secured to the insulating base 38, in proximity to its lower transverse edge, are three angular connector plates 88, which are retained in place by the binding screws 89. Each of these spaced connector plates 88 is provided with a connector screw 90 which is carried by the outer projecting end of the plate.

10 In Figs. 1 and 4, the projecting end 79^a of the rod 79 is illustrated as having rigidly mounted thereon an arm 91 which is provided with a bifurcated end 92 that loosely receives the stem 30 connected to the diaphragm 26. The outer end of this stem 30 is screw threaded, as at 93, for receiving the adjustable nut 94, as illustrated. This stem 30 is further provided with a washer 95, which is held in position by the pin 96, passing through the stem 30, and by the compression spring 97 which bears thereagainst at its lower end and against the bifurcated end 92 of the arm 91, at its upper end.

15 In Fig. 1, the wiring system is illustrated as being properly connected to the various elements previously described while in Fig. 3 this wiring system is illustrated diagrammatically for better enabling a person to trace the same. Three main feed lines, A, B, and C, are illustrated as being connected to the respective contact plates 88, by means of the binding screws 89. Each one of the screws 88, carried by the arms 81^a of the clamps 81, is connected to one of the contact plates 88, by a pigtail 99. The contact plates 75 have connected thereto, as by means of the binding screws 74, feed lines —a—, —b— and —c— which are intended 20 to lead to a motor, not shown, which is employed for driving a compressor, not shown. It will be noted that the motor feed wire —a— and the line wire A are intended to be connected by one of the switch blades 86, while the motor feed wires —b— and —c— are intended to be connected to the main line wires B and C respectively by the remaining two switch blades 86. It might be well to note at this point that 25 this three-wire system is intended to be employed for a three-phase motor and it is to be understood that the motor feed wire —b— and the main feed line B, with their coating switch elements and binding posts, may be eliminated if the compressor is driven by a single phase motor.

30 In Fig. 3 there is shown a thermostatic unit, designated in its entirety by the numeral 100, and this thermostatic unit consists of a thermostatic bar 101 which is connected by a wire 102 to a binding post 103 carried by the insulator base 38. The contact 35 104, associated with the thermostatic bar 101, is connected by a wire 105 to a binding post 106, carried by the insulator base

38 while the second contact bar 107 is connected by a wire 108 with a binding post 109, carried by the insulator base 38. It is to be understood that this thermostatic bar 101 is formed of a suitable substance or material for causing the same to be influenced by a change in temperature and that such changes will cause the bar to flex for engaging the different contact elements 40 104 and 107 for closing the circuit from the wire 102 to either of the wires 105 or 108. It is to be understood that this thermostatic unit 100 is to be positioned within the space intended to be cooled by the refrigerating system controlled by this apparatus.

45 The binding post 106 is to be connected to one lead of the solenoid coil 46 by a wire 110 and the remaining lead wire for the coil 46 is to be connected to the binding screw 71 of the switch blade 70 by means of a wire 111. The binding screw 64, electrically connected to the contact post 66 by the bracket 65, is intended to be connected to the contact plate 88, associated with the main feed line C, by the wire 112. The binding post 109 is to be connected to one lead of the coil 52 by means of the wire 113 while the remaining lead of the coil 52 is to be connected to the binding screw 74, associated with the motor feed line —c—, by means of the wire 114. The remaining binding post 103 is to be directly connected to the contact plate 88, in series with the main feed line A, by means of the wire 115. It is now believed that the wiring system has been clearly described and a person skilled in the art will be able to trace the same without any difficulty.

50 The operation of the apparatus embodying this invention is as follows:

55 The apparatus will first be considered with all of the elements arranged as illustrated in Figs. 1 to 3 inclusive. It will be noticed that the solenoid core 47 has been raised and is retained in this elevated position by the pawl 55. With the pawl in this position, the switch blade 70 is out of engagement with the contact post 66. The raising of the solenoid core 47 has rocked the lever 59 for moving the valve 24 away from the valve seat 17. With this valve unseated, water is allowed to flow from the pipe 5 through the nipples 8 and 10 into the pipe 15, by way of the coupler 11, and the water is then fed to the compressor. The water pressure in the coupler 11 will flex the diaphragm 26, forcing upwardly upon the same, and the stem 30 will be elevated. The compression spring 97, carried by the stem 30, will operate upon the arm 91 for rotating the rod 79. Rotation of this rod 79 will move the various brushes 87, carried by the blades 86, into engagement with the various contact plates 75 whereupon all of the line wires, A, B 60 110 115 120 125 130

and C, will be connected with the motor line —a—, —b— and —c— respectively for operating the compressor motor. The compressor will thereby be driven by this electric motor.

It will now be considered that the thermostatic bar 101 is positioned, as illustrated in Fig. 3, halfway between the contacts 104 and 107. After the refrigerating plant has been operated for bringing the refrigerator space down to the desired temperature, the thermostatic bar 101 will be flexed to the left and will engage the contact 107. When these elements, 101 and 107, are connected, a shunt circuit will be established from the main feed line A, through the wires 115 and 102 to the thermostatic bar 101. The contact 107 will be connected by the wire 108 to the magnetic coil 52 which in turn will be connected, by the wire 114, the binding screw 74, the contact plate 75, the brush 87, the switch blade 86, and the pigtail 99 to the main feed line C. Current will flow through this circuit for energizing the magnetic coil 52 and the magnetic flux created thereby will attract the pawl 55 for disengaging the same from the block 49 carried by the solenoid stem 48. The solenoid will then be permitted to drop and upward pressure upon the end 61 of the lever 59 will cease. The valve stem 23 and the valve 24 will then move upwardly, due to the pressure of water against the valve 24, and the supply of water from the pipe 5 will be cut off, thereby preventing the flow of water to the compressor. As the water passes out of the coupler 11, the pressure employed for retaining the diaphragm 26 flexed upwardly will cease and the stem 30 will be allowed to drop, due to the pressure of the spring 31. Downward movement of this stem 30 will cause the nut 94 to engage the bifurcated end 92 of the arm 90 and the rod 79 will be caused to rotate. This rotary movement of the rod 79 will cause all of the brushes 87 to be moved out of engagement with the contact plates 75 and current will cease to flow through the motor feed lines —a—, —b— and —c— for stopping the motor employed for driving the compressor.

It will now be noted that the solenoid core 47 has dropped and that the normal diameter of the block 49 carried by the core stem 48 will have moved the pawl 55 a sufficient distance for causing the switch blade 70 to engage the contact post 66. The blades 86 and 70 are now all in the positions illustrated in dotted lines in Fig. 3. After the temperature rises in the refrigerator space, the thermostatic bar 101 will be flexed until it engages the contact 104 whereupon a circuit will be established from the main feed line A, through the

wire 115 to the post 103 and through the wire 102 to the thermostatic bar 101. Current will then flow from this bar 101 to the contact 104 and through the wires 105 and 110 to one lead of the solenoid coil 46. The second lead of this solenoid coil will be connected by the wire 111 to the binding screw 71 and the switch blade 70, illustrated in dotted lines, will engage the contact post 66 for causing the current to flow through the wire 112 to the main feed line C. It will now be seen that the solenoid coil 46 will be energized and that the solenoid core 47 will rise for permitting the pawl 55 to engage the notch 50 formed in the block 49. The rising of this core 47 will elevate the end 61 of the lever 59 and thereby will force the valve 24 off of the seat 17. The unseating of this valve will permit water to flow to the compressor. The water pressure in the coupler 11 will cause the diaphragm 26 to be flexed upwardly for operating the stem 30 and the rod 79. Rotation of this rod 79 will cause the switch blades 86 to move for placing the brushes 87 into electrical engagement with the plate 75 whereupon current will again be applied to the compressor motor.

It is to be understood, while the water is flowing from the supply pipe 5 to the compressor feeding pipe 15, the water pressure will vary in the coupler 11. Should the pressure increase, the stem 30 will, of course, be moved upwardly a greater distance, but due to the spring connection 97 between this stem and the arm 91 and the springs 84 between the arms 81^a and the switch blades 86, the rod 79 will be permitted to rotate after the brushes 87 have been placed into engagement with the contact plates 79 without causing damage to the blades 86. The diaphragm 26 is intended to be influenced by the water pressure within the coupler 11 in such a manner that the three-pole switch will be retained in its circuit closing position until the water pressure should happen to drop to a predetermined low point, such as one or two pounds pressure, whereupon the diaphragm will return to its normal position operating the rod 79 for moving the switch blades 86 and brushes 87 into their circuit breaking positions. It will, therefore, be seen that should the water pressure drop too low or should the water entirely cease to flow, the compressor motor will be stopped and the compressor will be prevented from operating without any supply of water.

The valve 33 has been provided in the compressor feed pipe 15 for controlling the amount of water fed to the compressor entirely independently of the automatic apparatus previously described.

It is now believed that the construction, manner of assembling, and operation of the

various elements embodying this invention will be understood from the above detail description and, therefore, no further explanation is deemed necessary.

5 It is to be understood that the form of the invention herewith shown and described is to be taken as a preferred example of the same, and that various changes in the shape, size, and arrangement of parts may 10 be resorted to without departing from the spirit of the invention or the scope of the subjoined claims.

Having thus described the invention, I claim:

15 1. In a refrigerating apparatus, the combination with a water circulating system for a compressor and an electric wiring system for the compressor motor, of a valve normally seated by water pressure for controlling the flow of water through the circulating system, a lever operatively connected to said valve, thermostatically controlled electro-magnetic means for operating said lever for unseating said valve, a 20 pawl for holding said valve unseated, a weight connected to said pawl for normally holding the latter in a position in readiness to hold said valve unseated thermostatically controlled electro-magnetic means for moving said pawl into its inoperative position for permitting the valve to seat, a switch for controlling the flow of current through the electric wiring system, a water pressure operated diaphragm in the circulating system, and means for connecting the switch to said diaphragm whereby the latter will close said switch when the valve is unseated and will open said switch when the valve is seated.

40 2. In a refrigerating apparatus, the combination with a water circulating system for a compressor and an electric wiring system for a compressor motor, of a valve normally seated by water pressure for controlling the flow of water through the circulating system, a lever operatively connected to said valve, a solenoid coil, a movable core for said solenoid engaging said lever for unseating said valve when the coil is energized, 45 a circuit for the solenoid coil, thermostatic means for closing the circuit to the solenoid coil, a pivoted pawl for engaging said core to hold said valve unseated, means connected to said pawl for normally retaining it in a position for engaging said core, a magnet for moving the pawl out of engagement with said core for permitting said valve to seat, a circuit for said magnet, thermostatic means for closing the circuit to said magnets, a switch for controlling the flow of current through the electric wiring system, a water pressure operated diaphragm in the circulating system, and means for connecting the switch to said diaphragm 55 whereby the latter will close the said switch

when the valve is unseated and will open said switch when the valve is seated.

3. In a refrigerating apparatus, a water circulating system, a valve in the circulating system normally closed by the water pressure, a stem for said valve, a lever operatively connected to said stem, a solenoid coil, a movable core for said coil engaging said lever for opening said valve when the coil is energized, a pivotal pawl associated with said core and adapted to engage the latter for holding said valve open, means connected to said pawl for normally retaining it in a position for engaging said core, a magnet for moving the pawl out of engagement with the core for permitting the valve to close, and thermostatic means for causing said solenoid and magnet to operate independently.

4. In a refrigerating apparatus, a water circulating system, a valve in the circulating system normally closed by the water pressure, a stem for said valve, a lever operatively connected to said stem, a solenoid coil, a movable core for said coil loosely engaging said lever for opening said valve when the coil is energized, a pivotal pawl associated with said core and adapted to engage the latter for holding said valve open, a weight connected to said pawl for normally retaining it in a position for engaging said core, a magnet for moving the pawl out of engagement with the core for permitting the valve to close, and thermostatic means for causing said solenoid and magnet to operate independently.

5. In a refrigerating apparatus, a water circulating system, a valve in the circulating system normally closed by the water pressure, a stem for said valve, a lever operatively connected to said stem, a solenoid coil, a wiring circuit for said coil, a movable core for said coil engaging said lever for opening said valve when the coil is energized, means for holding said valve open, means operatively connected to said last mentioned means for breaking the circuit to said solenoid coil after the holding means has moved into its operative position, and means for moving the valve holding means into its inoperative position for permitting the valve to close.

6. In a refrigerating apparatus, a water circulating system, a valve in the circulating system, normally closed by the water pressure, a stem for said valve, a lever operatively connected to said stem, a solenoid coil, a wiring circuit for said coil, a movable core for said coil engaging said lever for opening the valve when the core is energized, a pawl for holding said valve open, a switch operatively connected to said pawl for breaking the circuit to said solenoid coil after the pawl has been moved into its operative position, and electric means for

moving the valve holding pawl into its inoperative position for permitting the valve to close.

7. In a refrigerating apparatus, a water circulating system for a compressor, a wiring system for a compressor motor, a switch for the wiring system, a pressure operated diaphragm in the circulating system, a stem carried by said diaphragm, an arm carried by said switch, and means for connecting the diaphragm stem to the switch arm in such a manner that the switch will be closed when the pressure in the circulating system rises above a predetermined point and the switch will be opened when the pressure drops below said predetermined point, said connection between the diaphragm stem and the switch arm permitting movement of the stem, due to increasing pressure upon said diaphragm, without influencing the switch.
8. In a refrigerating apparatus, a water

circulating system for a compressor, a wiring system for a compressor motor, a switch for the wiring system, a pressure operated diaphragm in the circulating system, a stem carried by said diaphragm, an arm having a bifurcated end carried by said switch with the diaphragm stem located between the bifurcations of said arm, and resilient means carried by said stem and engaging the bifurcated end of said arm whereby the switch will be closed when the pressure in the circulating system rises above a predetermined point and the switch will be opened when the pressure drops below said predetermined point, the resilient means permitting movement of the stem after the switch is closed, due to increase in pressure upon the diaphragm, without influencing the switch.

In testimony whereof I affix my signature.

CHARLES SCHWEINLE.
